* cited by examiner

Primary Examiner—Celia Murphy(74) *Attorney, Agent, or Firm*—Marshall A. Lerner, Esq.; Finn T. Simmensen, Esq.; Kleinberg & Lerner, LLP(57) **CLAIM**

The ornamental design for a shoe bottom, as shown and described.

DESCRIPTION

FIG. 1 is a perspective view of a shoe bottom showing my new design;

FIG. 2 is a bottom plan view thereof;

FIG. 3 is a left side elevational view thereof;

FIG. 4 is a right side elevational view thereof;

FIG. 5 is a front elevational view thereof; and,

FIG. 6 is a rear elevational view thereof.

Broken lines in the figures are for illustrative purposes only and form no part of the claimed design.
